(57) **CLAIM**

We claim the ornamental design for a bottle, as shown and described.

DESCRIPTION

FIG. 1 is a top, front perspective view of a bottle of the new design;

FIG. 2 is a bottom, front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a detail of a portion of the claimed design taken from FIG. 3, shown at an enlarged scale.

The broken lines shown in the drawings illustrate a portion of the bottle which forms no part of the claimed design.
